UNITED STATES PATENT OFFICE

91,343

DESIGN FOR AN ADVERTISING SIGN

Ewald Zeiser, Webster Groves, Mo.

Application November 4, 1933. Serial No. 49,651

Term of patent 7 years

To all whom it may concern:

Be it known that I, EWALD ZEISER, a citizen of the United States, and a resident of Webster Groves, county of St. Louis, and State of Missouri, have invented a new, original, and ornamental Design for Advertising Signs, of which the following is a specification, reference being had to the accompanying drawing forming part thereof.

In the drawing, Fig. 1 is a front elevational view; Fig. 2 is a side view, and Fig. 3 is a perspective view of an advertising sign illustrating my new design.

I claim:

The ornamental design for an advertising sign as shown.

EWALD ZEISER.
